Primary Examiner — Katherine A Holbrow*Assistant Examiner* — Riya Salil Kamat**CLAIM**

The ornamental design for an exercise machine arm joint, as shown and described.

DESCRIPTION

FIG. 1 is a top front perspective view of an exercise machine arm joint showing my new design;

FIG. 2 is a bottom rear perspective view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view thereof;

FIG. 8 is a back elevational view thereof;

FIG. 9 is a top front perspective view of the exercise machine arm joint in a folded configuration; and,

FIG. 10 is a bottom rear perspective view thereof.

The broken lines showing the exercise machine body and arms in FIGS. 1-10 show environment and form no part of the claimed design.

1 Claim, 10 Drawing Sheets(56)
